P. R. WHEELER,
INTERNAL COMBUSTION ENGINE,
APPLICATION FILED SEPT. 25, 1918.

1,393,593.

Patented Oct. 11, 1921.

UNITED STATES PATENT OFFICE.

PORTIUS R. WHEELER, OF PEORIA, ILLINOIS.

INTERNAL-COMBUSTION ENGINE.

1,393,593.

Specification of Letters Patent. Patented Oct. 11, 1921.

Application filed September 25, 1918. Serial No. 255,544.

To all whom it may concern:

Be it known that I, PORTIUS R. WHEELER, a citizen of the United States, and a resident of Peoria, in the county of Peoria and 5 State of Illinois, have invented certain new and useful Improvements in Internal-Combustion Engines, of which the following is a full, clear, and exact description, reference being had to the accompanying drawing, forming a part of this specification.

My invention relates more particularly to that class of internal combustion engines operating upon the two-stroke-cycle principle wherein a power impulse is imparted to the 15 piston for every two strokes thereof.

One object of my invention is to so arrange the various parts of the engine that the suction stroke thereof will be continuous during substantially a half revolution of 20 the crank shaft.

Another object of my invention is a provision of means whereby a portion of the charge sweeps the ignition element thus insuring the proper ignition of the charge.

25 Another object of my invention is to arrange the various parts of the engine so that they are easily accessible for repair, renewal or inspection, should occasion arise.

Other objects of my invention will appear 30 and be described in the specification.

The novelty of my invention will be hereinafter more fully set forth and specifically pointed out in the claims.

In the accompanying drawing Figure I 35 is a sectional end elevation of an engine embodying my invention, the parts being shown in their proper relation and position at the point of ignition.

Fig. II is a view similar to Fig. I, some 40 of the parts being shown broken away, the position and relation of the parts being proper for a position about midway on the suction and compression stroke.

The same numerals of reference are used 45 to indicate identical parts in both figures.

To illustrate one form of engine in which my invention may be embodied, 1 represents a cylinder structure composed of the inner cylinder wall 2, water jacket wall 3, 50 valve pocket 4, and other parts to be later described. The cylindrical piston 5 is mounted within the cylinder and connected by means of connecting rod 6 to the crank shaft 7 which is mounted in the crank case 8.

55 The upper portion of the cylindrical piston 5 is provided with exhaust ports 9, suc-

tion and transfer ports 10, and head 11, this head being provided with a central opening and a stuffing box 12 through which, and the central opening in the head 11, a tube 13 is passed, the tube being held in the member 14, and carrying a piston head 15 at its lower end.

The member 14 is secured to the upper portion of the cylinder structure as by 65 means of cap screws 16. The valve pocket 4 is provided with the valve 17 which may be the usual form of puppet valve, or any other suitable form of valve and is provided with a downwardly extending stem 18 and 70 spring 19 which serves to normally hold the valve 17 against its seat. The valve actuating mechanism comprises a link 20 which is connected to the connecting rod 6 at one end and to the bell crank 21 at the 75 other end, the bell crank 21 being mounted upon the valve lifter guide 22 as clearly shown, the guide carrying the valve lifter 23 which is adjustable as by means of the cap nut 24 and lock nut 25 so that the parts 80 may be set to insure the proper operation of the valve 17.

At the head end of its travel one of the exhaust ports 9 of the cylindrical piston 5 registers with the ignition port 26 as shown 85 in Fig. I and any suitable form of ignition device such as the spark plug 27 may be provided for the ignition of the charge, while at the lower end of the travel of the cylindrical piston 5 one of the exhaust ports 90 9 registers with the exhaust port 28 through which the spent gases pass to the exhaust manifold 29.

An annular inlet port 30 is formed in the cylinder structure and communicates with 95 the valve pocket 4 and with the inlet and transfer ports 10 of the cylindrical piston 5.

It is to be noted that the inlet and transfer ports 10 are of such length and location that immediately after the beginning of the registration of the exhaust port 9 with the exhaust passage 28, the lower edge of the inlet and transfer ports 10 pass below the lower edge of the piston head 15 105 to permit the charge to transfer as will be later described.

It is also to be noted that the piston head 15 is at all times stationary with relation to the cylinder structure and to facilitate the 110 control of its temperature during the operation of the engine it may be provided

with a water space 31 and have water inlet passage 32 and outlet passage 33, the water passage 32 communicating with the pipe 34 which, as shown in Fig. I may be carried by the cap nut 35 which holds the tube 13 in place in the member 14, the cap nut 35 being also provided with one member of a union 36 by means of which a manifold 37 may be attached.

10 The water outlet passages 33 may communicate with the space between the tube 34 and the tube 13, the upper portion of the latter being provided with ports 38 which communicate with an outlet 39, which is connected to the main water outlet manifold 40.

A suitable inlet water manifold 41 is connected to the structure to supply the cooling water or other medium to the water jacket 42 of the cylinder structure.

20 The fuel inlet 43, over which any suitable form of carburetor may be attached, communicates with the valve pocket 4, the passage being controlled by the valve 17.

25 Any suitable hand hole cover 44 is provided to give access to the valve adjusting mechanism previously described and a hand hole cover 45 may be provided to give access to the valve operating mechanism.

30 I will now proceed to describe the operation of the engine. Assuming the parts to be in the position shown in Fig. I and assuming that it is desired to start the engine, the crank shaft is set in motion whereupon 35 the cylindrical piston, through the connection previously described, is drawn downward during the first half revolution, at which point the valve operating mechanism opens valve 17, the upstroke of the piston

40 causing a partial vacuum between the piston head 15 and the head 11, the partial vacuum drawing the required charge through the inlet opening 43, valve pocket 4, annular inlet port 30, and inlet and transfer ports 10.

45 When the cylindrical piston has again reached the position shown in Fig. I, the valve 17 closes, confining the charge within the engine and the continued movement of the crank shaft compresses the charge above 50 the piston head 15 until the transfer ports 10 pass this piston head and permit the escape of the compressed charge to the space below the piston head 15 whereupon the upstroke of the piston 5 compresses the charge 55 for the combustion.

During the compression of the charge for combustion as just described, the valve 17 again opens and the space above the piston 15 is again filled with the next succeeding 60 charge of fuel.

The combustion of the charge forces the piston downward until the exhaust ports 9 come into registration with the exhaust passage 28, releasing the pressure within the 65 combustion chamber, extinguishing the

flame of combustion due to the release of the pressure and, as previously described, immediately after the release of the pressure and during the continued downward motion of the piston the inlet and transfer 70 ports 10 pass below the piston head 15 thereby releasing the compressed charge above the piston head 15, which charge by entering the combustion chamber sweeps the spent gases from the previous combustion 75 out through the exhaust passage thereby scavenging the combustion chamber for the next succeeding ignition.

It is to be noted that one of the inlet and transfer ports 10 is arranged in line with 80 the ignition port 26 and further that as this port travels downward past the piston head 15 a portion of the charge sweeps into the ignition port 26, driving out the spent gases and filling this space with fresh fuel for 85 the next succeeding ignition.

Any suitable cover 46 may be mounted over the upper portion of the cylinder structure to prevent foreign matter from finding its way into the working parts of the engine and to present a properly finished exterior.

It is to be noted that the water jacket space of the cylinder structure is carried upward above the top of the combustion chamber so that the space above the piston head 15 is heated, the result being that temperature of the water leaving the cylinder structure is reduced while the temperature of the entering charge is increased to thoroughly 100 vaporize the entering fuel.

Having thus fully described my invention, I claim:

1. In an internal combustion engine the combination of a cylinder structure, a cylindrical piston mounted therein and connected to operate a crank shaft, a stationary piston head mounted in said cylindrical piston, a tubular support for said stationary piston head, a carrying member for said support and attached to said cylinder structure, a tube passing through said tubular support for introducing a cooling medium to said stationary piston head, a head carried by said cylindrical piston and coöperating with said stationary piston head to form a charging cylinder, an inlet and transfer port communicating with said charging cylinder and a valve controlled inlet passage for the admission of the fuel, an exhaust port opening 110 from the combustion chamber and adapted to register with an exhaust passage of said cylinder structure.

2. In an internal combustion engine the combination of a cylinder structure provided with inlet and exhaust passages, a cylindrical piston mounted in said cylindrical structure and connected to operate a crank shaft, a stationary piston head mounted in said cylindrical piston for dividing it into a charg- 125

- ing cylinder and a combustion space, a support for said stationary piston head said support passing through the charging portion of said cylinder piston, a removable head 5 rounding said support and carried by said cylindrical piston, cooling medium inlet and outlet passages in said support and communicating with a cooling medium space in said stationary piston head, a valve in the inlet 10 passage of said cylinder structure, and connections between a moving part of the engine and a valve lifter whereby said valve may be raised from its seat during the suction stroke of the engine.
- 15 3. In an internal combustion engine the combination of a cylinder structure, a cylindrical piston therein and connected adjacent one end to operate a crank shaft, a removable head in the other end of the cylindrical piston and provided with a centrally arranged stuffing box, a support carried by
- the cylinder structure, a tube depending from the support and passing through the stuffing box of the head of the cylindrical piston, a piston head carried by the lower 25 end of the tube and provided with a cooling medium chamber the piston head dividing the cylindrical piston into charging and combustion cylinders, means for circulating a cooling medium through the piston head 30 and its tubular support, an admission and transfer port in the cylindrical piston, an ignition device carried by the cylinder structure and registering with the transfer port during the transfer of a charge whereby the 35 charge will sweep the ignition device, and an ignition and exhaust port registering with the ignition device for the ignition of the charge and with an exhaust port in the cylinder structure for the exhaust of the 40 charge.

PORTIUS R. WHEELER.
